UNITED STATES PATENT OFFICE.

GEORGE GOCHIER, OF JOHNSTOWN, PENNSYLVANIA.

WATER-WHEEL.

SPECIFICATION forming part of Letters Patent No. 678,869, dated July 23, 1901.

Application filed November 6, 1900, Serial No. 35,599. (No model.)

To all whom it may concern:

Be it known that I, GEORGE GOCHIER, a resident of Johnstown, in the county of Cambria and State of Pennsylvania, have invented 5 certain new and useful Improvements in Water-Wheels; and I do hereby declare the following to be a full, clear, and exact description of the invention, such as will enable others skilled in the art to which it applies to make and use the same.

My invention relates to an improved water-wheel, and more particularly to an overshot water-wheel, the object of the invention being to provide a wheel of this character which 15 will utilize to the fullest extent the weight of the water to turn the wheel and which will completely discharge the water at the lowest point, so as to offer the least possible resistance to the return of the buckets to the 20 point of filling.

With this object in view the invention consists in certain novel features of construction and combinations and arrangements of parts, as will be more fully hereinafter described, 25 and pointed out in the claims.

In the accompanying drawings, Figure 1 is a side view, partly in section, illustrating my improvements. Fig. 2 is a front view, and Fig. 3 is a view in vertical section of one side 30 of the wheel.

k k represent collars secured on a shaft *m* and spaced a suitable distance apart, and radial spokes *s* are secured to the collar *m* and are secured at their outer ends between an 35 inner flat ring *j* and an outer angle-iron ring *h*, and inner rings *g* of slightly less diameter than the internal diameter of rings *j* are secured to the inner faces of spokes *s* and have secured between them and the ring *j* a cylinder 1, extending from one set of spokes to the other, and a series of plates or partitions 2, preferably in the form of a compound curve in cross-section, are secured between rings *j* and around the cylinder 1 to form rigid buck- 40

ets 3 for the water, as clearly shown in Fig. 1.

A series of alined bearing-sleeves *f* are secured around the periphery of ring *h* for spindles *b*, one which is provided above or in the entrance of each bucket 3. Circular 50 disks or rollers *a* are secured on the spindles *b* beside rings *j*, and are provided in their inner faces with semicircular grooves for the

reception of the respective ends of semicircular buckets *c*, which latter are secured in the grooves of the disks or rollers *a* by any 55 approved means.

Below each series of disks or rollers *a* a tripper is located, and each tripper comprises a base *p*, to which a bar *n* is hinged by a pin *r*, as shown, and a rubber block *o* or spring, 60 if desired, is located between the base *p* and bar *n* to press the latter up against the rollers *a*, the frictional engagement thereof serving to rotate the disks or rollers *a* and empty buckets *c*, as will now be explained.

Water is discharged into buckets *c* and 3 at the top of the wheel, and it will be seen that owing to the pivotal support of the buckets *c* they will be maintained full of water until upset by the trippers at the bottom of 70 the wheel, but the buckets 3 will discharge their contents throughout practically their entire movement, from the highest to the lowest point of the wheel, but owing to the peculiar position of buckets *c* the buckets 3 75 will discharge into the buckets *c* immediately below them, and the force of such discharged water will add to the power of the wheel, and when buckets *c* reach their lowest point they will engage the upper face of bar *n*, and 80 the frictional engagement thereof against rollers or disks *a* will revolve the latter to turn the buckets over, thus emptying them completely, so that no resistance save that of the weight of the buckets is offered to the 85 rotation of the wheel.

Various slight changes might be resorted to in the general form and arrangement of the several parts described without departing from the spirit and scope of my invention, 90 and hence I would have it understood that I do not wish to limit myself to the precise details set forth, but consider myself at liberty to make such slight changes and alterations as fairly fall within the spirit and scope of 95 my invention.

Having fully described my invention, what I claim as new, and desire to secure by Letters Patent, is—

1. In a water-wheel, the combination of a 100 series of freely-revoluble buckets, a fixed bucket behind each revoluble bucket and adapted to discharge into the latter as the wheel turns and means for positively rotating

each revoluble bucket when it reaches its lowest position to discharge its contents.

2. A water-wheel comprising framework, an annular series of fixed buckets and a series of freely-revoluble buckets disposed over the inlets of the fixed buckets so as to receive water from the latter as the wheel revolves.

3. A water-wheel comprising framework, an annular series of fixed buckets and an annular series of buckets mounted axially to revolve freely and alternating with the walls of the fixed buckets.

4. A water-wheel comprising framework, an annular series of fixed buckets, each having its walls disposed tangentially with relation to the wheel, and an annular series of buckets each mounted to rotate freely in advance of one wall of each fixed bucket.

5. In a water-wheel, the combination of a frame, a series of fixed buckets, a series of movable buckets mounted in front of the fixed buckets so as to receive water therefrom as the wheel revolves, each of said movable buckets comprising end disks or rollers, shafts

25 passing centrally through said disks or rollers and revolvably mounted on the frame so as to permit the movable buckets to rotate freely and completely, and trippers disposed

in the paths of said end disks or rollers for rotating the latter and the movable buckets 30 when they reach the lowest point of their movement.

6. In an overshot water-wheel, the combination with a cylinder, spokes connecting the cylinder and drive-shaft, rings on each end 35 of said cylinder and partitions or plates secured on the cylinder between the rings forming rigid buckets, of buckets pivotally supported in the entrance of the rigid buckets and a tripper for upsetting said last-mentioned buckets when they reach their lowest point.

7. In a water-wheel, the combination with a wheel, and a series of pivotally-supported buckets carried thereby, of a tripper adapted 45 to upset said buckets, comprising a base, a bar hinged thereto and elastic material between said base and bar to press the latter against the buckets.

In testimony whereof I have signed this 50 specification in the presence of two subscribing witnesses.

GEORGE GOCHER.
